(57) **CLAIM**

The ornamental design for an 8-sided flat panel array antenna, as shown and described.

DESCRIPTION

FIG. 1 is a perspective front view of the antenna.

FIG. 2 is a perspective back view of the antenna.

FIG. 3 is a front view of the antenna.

FIG. 4 is a left side view of the antenna, the right side being a mirror image; and,

FIG. 5 is a back view of the antenna.

The broken lines showing a radome, radio mount and fastener connections are for environmental purposes only and form no part of the claimed design.
